(57) **CLAIM**

The ornamental design for a poultry cooking appliance, as shown and described.

DESCRIPTION

FIG. 1 is a perspective view of a poultry cooking appliance showing our new design;

FIG. 2 is a top plan view thereof;

FIG. 3 is a bottom view thereof;

FIG. 4 is a front elevational view thereof; and,

FIG. 5 is a side elevational view thereof.

The rear elevational view is a mirror image of the front elevational view illustrated in FIG. 4; the side not illustrated is a mirror image of the side illustrated in FIG. 5 and the broken line showings form no part of the claimed design.
